Primary Examiner — Kevin K Rudzinski*Assistant Examiner* — J. Thorn, Sr.(74) *Attorney, Agent, or Firm* — Arent Fox LLP(57) **CLAIM**

The ornamental design for a temperature regulating garment, as shown and described.

DESCRIPTION

FIG. 1 is a front perspective view of a first embodiment of a temperature regulating garment;

FIG. 2 is a front elevational view thereof;

FIG. 3 is rear elevational view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a second embodiment of a temperature regulating garment;

FIG. 9 is a front elevational view thereof;

FIG. 10 is rear elevational view thereof;

FIG. 11 is a left side view thereof;

FIG. 12 is a right side view thereof;

FIG. 13 is a top view thereof; and,

FIG. 14 is a bottom view thereof.

The broken lines in the drawings depict portions of the temperature regulating garment that form no part of the claimed design.

1 Claim, 10 Drawing Sheets(56)
